UNITED STATES PATENT OFFICE.

ROBERT S. RISDON, OF SAN FRANCISCO, CALIFORNIA, ASSIGNOR OF ONE-HALF TO MARY LAWSON, OF SAN FRANCISCO, CALIFORNIA.

AUTOMATIC HEADLIGHT CONTROL.

1,225,494.

Specification of Letters Patent.

Patented May 8, 1917.

Application filed September 24, 1915. Serial No. 52,423.

To all whom it may concern:

Be it known that I, ROBERT S. RISDON, a citizen of the United States, residing at San Francisco, in the county of San Francisco and State of California, have invented new and useful Improvements in Automatic Headlight Controls, of which the following is a specification.

This invention relates to headlights and 10 more particularly to supporting and controlling means therefor.

The principal object of the invention is to provide a simple and efficient mounting mechanism connected in such manner to the 15 front axle stubs that the lights will be moved so that their rays are projected at right angles to the axis of the wheels and in the direction of movement of the car, whereby the light will not be projected at a tangent 20 to the travel of a vehicle when making a turn.

Another object of the invention is to provide a device of this character which may be attached to any type of motor vehicle 25 and which embodies novel features in the manner of mounting and supporting the light.

Further objects of the invention will appear as the following specific description is 30 read in connection with the accompanying drawings which form a part of this application, and in which—

Figure 1 is a front elevation showing the application of the invention to an ordinary 35 automobile.

Fig. 2 is a detail side elevation of one of the mounting brackets and its associated parts removed from the vehicle.

Fig. 3 is a vertical sectional view taken 40 therethrough.

Fig. 4 is a perspective view of one of the mounting brackets.

Fig. 5 is a plan view of the bearing disk.

Fig. 6 is a fragmentary sectional view 45 showing the means for connecting the flexible shaft to one of the stub axles and the relation between said parts.

Referring more particularly to the drawing, 1 represents the axle of an ordinary 50 motor vehicle and 2 the frame or chassis. Pivot upon the axle are the usual stub axles 3 of any preferred construction.

Secured to opposite sides of the frame 55 are the bracket arms 4 whose lower and inner ends extend horizontally and are con-

nected to any portion of the frame by the bolts 5. The outer and upper portion of each bracket extends parallel to the lower inner end and is in the shape of a circle or ring 6 having an internal shoulder 7 upon which the bearing disk 8 is supported. This disk is secured in position by means of the screws 9 and has formed in its upper and lower surfaces suitable races 10 for the reception of the anti-friction balls 11. The upper edge of the ring 6 is provided with an outward bevel 12 and seated upon the balls 11 on the upper face of the disk is a collar 13 having races 14 in its under face to receive the balls 11 and provided with an overhanging flange 15, whose under side is beveled to correspond with a bevel on the upper face of the ring. The ring is also provided with a depending annular flange 16 beveled upon the inner side to correspond with the external bevel of a collar 17 seated against the balls 11 on the under side of the disk 8. The collar 13 as well as the collar 16 and disk 8 are provided with external apertures to receive a vertical shaft 18 formed integrally with the lamp bracket 19 upon which the lamp 20 is supported. This shaft extends through the collars and disk and is threaded upon its lower end to receive adjusting and locking nuts 21 and 22 respectively, and is also provided with an aperture 23 to receive a locking key, whereby a flexible shaft 24 may be coupled therewith. The opening in the collar 17 is somewhat enlarged at its lower end to receive a spiral spring 24' which rests against the inner end of the enlarged part of the opening and against the adjusting nut 21. This spring firmly holds both collars in contact with the balls on opposite sides of the disk 8 and prevents rattling of the parts.

As shown, the lower end of the flexible shaft 24 is connected to an arm 25 secured directly to the adjacent stub axle so as to 100 rotate therewith. When the wheels are turned to round a curve in either direction, the arms 25 will also be turned and through the flexible shaft the shaft 18 will be rotated an equal distance in the same direction, thus turning the lamps on both sides of the machine so that they will follow all movements of the wheels. The overhanging flange 15 of the collar and the corresponding flange 16 upon the ring eliminate to a great 105 110

extent the accessibility of dust and dirt and water to the bearings, thereby insuring longevity of these parts and eliminating necessity of frequent adjustments.

5 The lamps 20 are preferably connected by a rod or bar 27 so as to insure uniformity of movement and if desirable, only one flexible shaft 24 may be employed, the action of the lamps being the same as heretofore described.

What is claimed is:—

10 The combination with a vehicle frame and steering axles therefor, of mounting brackets secured to opposite sides of the frame and each embodying a fixed ring having beveled and outwardly sloping top and bottom bearing faces, bearing plates detachably

20 mounted in said brackets, lamp-supporting shafts extending through said bearing plates, operating connections between said shafts and the steering axles, and bearing collars arranged above and below said bearing plates and rings, surrounding said shafts, and provided with outwardly sloping beveled bearing faces corresponding and 25 operating with the beveled faces of the fixed rings.

In testimony whereof I affix my signature in presence of two witnesses.

ROBERT S. RISDON.
